Primary Examiner — Susan Bennett Hattan*Assistant Examiner* — Leanne Was(74) *Attorney, Agent, or Firm* — Banner & Witcoff, Ltd.(57) **CLAIM**

We claim the ornamental design for a fan grille, as shown and described.

DESCRIPTION

FIG. 1 is a perspective view of a fan grille showing our new design;

FIG. 2 is a bottom plan view thereof; and,

FIG. 3 is a side elevation view thereof.
